(57) **CLAIM**

The ornamental design for lanyard for a mask or eyewear, as shown.

DESCRIPTION

FIG. 1 is a perspective view of a first embodiment of lanyard for a mask or eyewear of the present invention shown attached to a mask while being worn;

FIG. 2 is another perspective view thereof shown attached to eyewear while being worn;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view of a second embodiment of lanyard for a mask or eyewear of the present invention shown attached to a mask while being worn;

FIG. 10 is another perspective view thereof shown attached to eyewear while being worn;

FIG. 11 is a front view thereof;

FIG. 12 is a rear view thereof;

FIG. 13 is a left side view thereof;

FIG. 14 is a right side view thereof;

FIG. 15 is a top view thereof;

FIG. 16 is a bottom view thereof;

FIG. 17 is a perspective view of a third embodiment of lanyard for a mask or eyewear of the present invention shown attached to a mask while being worn;

FIG. 18 is another perspective view thereof shown attached to eyewear while being worn;

FIG. 19 is a front view thereof;

FIG. 20 is a rear view thereof;

FIG. 21 is a left side view thereof;

FIG. 22 is a right side view thereof;

FIG. 23 is a top view thereof;

FIG. 24 is a bottom view thereof;

(Continued)

FIG. 25 is a perspective view of a fourth embodiment of lanyard for a mask or eyewear of the present invention shown attached to a mask while being worn;

FIG. 26 is another perspective view thereof shown attached to eyewear while being worn;

FIG. 27 is a front view thereof;

FIG. 28 is a rear view thereof;

FIG. 29 is a left side view thereof;

FIG. 30 is a right side view thereof;

FIG. 31 is a top view thereof; and,

FIG. 32 is a bottom view thereof.

The broken lines showing the human form in FIGS. 1, 2, 9, 10, 17, 18, 25 and 26 illustrate environment that form no part of the claimed design. The remaining broken lines shown in all figures illustrate portions of the lanyard that form no part of the claimed design.
